DESIGN FOR A CASTER

Carl J. Johnson, Chicago, Ill.

Application January 8, 1938, Serial No. 74,145

Term of patent 7 years

To all whom it may concern:

Be it known that I, Carl J. Johnson, a citizen of the United States, residing at Chicago, in the county of Cook and State of Illinois, have invented a new, original, and ornamental Design for a Caster, of which the following is a specification, reference being had to the accompanying drawing, forming a part thereof.

Fig. 1 is a side view of a caster showing my new design.

Fig. 2 is a front view thereof.

Fig. 3 is a rear view of the same.

I claim:

The ornamental design for a caster, substantially as shown.

CARL J. JOHNSON.
